United States Patent

Des. 237,320

Patented Oct. 21, 1975

237,320

DRY SHAVER OR SIMILAR ARTICLE

Maarten Willem van Lelyveld, Drachten, Netherlands,
assignor to U.S. Philips Corporation, New York, N.Y.

Filed Aug. 27, 1973, Ser. No. 391,799

Claims priority, application Switzerland Mar. 1, 1973

Term of patent 14 years

Int. Cl. D95—03

U.S. Cl. D95—3 A

FIG. 1 is a perspective view of the dry shaver or similar article showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

I claim:

The ornamental design for a dry shaver or similar article, as shown and described.
